CHRISTMAS TREE ORNAMENT OR SIMILAR ARTICLE

George Burros, New York, N. Y., assignor to
Burros & Burros, Inc., New York, N. Y., a corporation of New York

Application February 25, 1950, Serial No. 8,127

Term of patent 7 years

(Cl. D29—1)

To all whom it may concern:

Be it known that I, George Burros, a citizen of the United States, residing at New York, in the county of Queens and State of New York, have invented a new, original, and ornamental Design for a Christmas Tree Ornament or Similar Article, of which the following is a specification, reference being had to the accompanying drawing, forming part thereof.

In the drawing

Fig. 1 is a front view of a Christmas tree ornament or similar article, in closed position, showing my new design;

Fig. 2 is a side view thereof; and

Fig. 3 is a bottom view thereof showing the Christmas tree ornament in an unfolded position.

I claim:

The ornamental design for a Christmas tree ornament or similar article, substantially as shown.

GEORGE BURROS.
